[57] CLAIM

The ornamental design for a fluid dispensing pump, as shown and described.

DESCRIPTION

FIG. 1 is a front perspective view of a fluid dispensing pump showing our new design, in which a semitransparent hinged cover of the pump is closed;

FIG. 2 is a front perspective view thereof, in which the semitransparent hinged cover is opened;

FIG. 3 is a front elevation view thereof;

FIG. 4 is a right side elevation view thereof;

FIG. 5 is a rear elevation view thereof;

FIG. 6 is a bottom plan view thereof;

FIG. 7 is a top plan view thereof; and,

FIG. 8 is a left side elevation view thereof.
